UNITED STATES PATENT OFFICE.

BENJAMIN M. NORMAN, OF CLEVELAND, OHIO.

DESIGN FOR A BOTTLE WARMER.

Application filed April 20, 1925. Serial No. 13,174. Term of patent 3½ years.

To all whom it may concern:

Be it known that I, BENJAMIN M. NORMAN, a citizen of the United States, residing at Cleveland, in the county of Cuyahoga and State of Ohio, have invented a new, original, and ornamental Design for a Bottle Warmer, of which the following is a specification, reference being had to the accompanying drawing, forming part thereof.

The figure is a side elevation of the bottle warmer showing my new design.

I claim:

The ornamental design for a bottle warmer, as shown.

BENJAMIN M. NORMAN.
